UNITED STATES PATENT OFFICE.

JAMES DUNN, OF PHILADELPHIA, PENNSYLVANIA, ASSIGNOR TO McNEELY COMPANY, OF PHILADELPHIA, PENNSYLVANIA, A CORPORATION OF PENNSYLVANIA.

FLESHING AND SLATING MACHINE.

No. 845,768.

Specification of Letters Patent.

Patented March 5, 1907.

Application filed March 25, 1905. Serial No. 251,989.

To all whom it may concern:

Be it known that I, JAMES DUNN, of Philadelphia, in the State of Pennsylvania, have invented certain new and useful Improvements in Flesching and Slating Machines, of which the following is a specification, reference being had to the accompanying drawings.

My improvements relate to flesching and slating machines of well-known types, wherein a skin is carried by an endless rubber band into close contact with a roll having knife-blades of steel or slate set angularly or spirally upon its surface. In such machines as heretofore constructed two workmen are required, one feeding the skins to the roll and another standing at the opposite end of the machine removing the skins as they are delivered by the roll. These machines are dangerous to one or the other of these workmen, according to the direction in which the roll rotates. In the older form of machine the lower side of the roll moves in the direction of the upper side of the endless band, making the machine very hazardous to the workman who feeds the skins to the machine. In the newer form of machine the roll rotates in the opposite direction, making the machine hazardous to the workman who receives the skins.

My invention is especially applicable to said newer form of machine, and consists in the addition thereto of a stripping device by means of which the removal of the skin from the machine upon its delivery by the roll is automatically effected, so that it is no longer necessary for a workman to remove the skins from the roll. Further, the stripping device acts as an obstacle, preventing any one from accidentally placing his hand near the inwardly-rotating lower side of the roll.

In the accompanying drawings, Figure I is a vertical central section of a machine having one embodiment of my invention applied to it. Fig. II is a similar partial section of a machine having another embodiment of my invention applied to it.

Referring to the form of machine disclosed in Fig. I, the parallel rollers 22, which carry the endless rubber band 3, are suitably journaled upon the table 1. Above the upper side of the band 3 and with its periphery nearly or quite in contact therewith is

mounted the main roll 4, which may be a flesching or slating roll of any construction. 55 As is well known, it is customary in these machines to provide rolls of differing construction and function according to the character of the skins to be handled, and my improvements are applicable to machines of this 60 type irrespective of the nature of the rolls which may be used for treating the skin.

Immediately in the rear of the roll 4 there is mounted a grip-roll 5, which consists of a grooved metallic roller mounted with its 65 lower surface below the normal level of the upper section of the endless band, against which it presses with corresponding tension. It is situated near to the roll 4 in order to lessen the space between the points where 70 the two rollers touch the band. Immediately beneath the roller 4 a pressure-roller 6 is mounted on vertically-sliding journal-boxes held up by twin slide-rods, of which one is shown at 7, operated by a treadle 8. The 75 pulleys and gears, by which the rolls are driven, are not shown in the drawings, their arrangement being well-known; but the direction in which the rolls rotate is indicated by arrows.

Thus far I have described only the parts of the machine as it has been ordinarily constructed prior to my invention. Its operation is well understood. The grip-roll 5 has its periphery rotating in the same direction 85 as the part of the endless band which it touches, and accordingly the skin between the two is drawn with the band, notwithstanding the rotation of the roll 4 in the opposite direction. The pressure-roller 6 when 90 lowered permits the skin to be advanced far enough to be caught by the grip-roll, and when this has been accomplished the pressure-roller is raised so as to increase the efficiency 95 of the action of the roll 4. In such a machine a workman usually stands in the rear in order to strip the skins, which tend to adhere to the grip-roll and must be removed therefrom manually. This operation is hazardous, because the grip-roll and the main roll 4 are necessarily near together. Their opposing 100 surfaces rotate inwardly, and if the hand of the workman who is removing the skin from the grip-roll remains too long upon the roll there is danger of serious accident. My invention 105 overcomes this danger and lessens or

does away with the necessity for the second workman in the rear of the machine. I mount a roller 10, having its surface provided with bristles or wire brushes in proximity to the grip-roll. It is driven by the pinion 11, meshing with the pinion 12, which engages a gear upon the end of the grip-roll, the direction of rotation being indicated by the arrow in Fig. I. By this roller 10 the skins are stripped from the grip-roll, so that they fall upon the endless band and are by it delivered over the edge of the machine without the necessity of manual intervention.

In Fig. II, I have shown an alternative form of my invention, in which in place of the brushing-roller 10 there is an endless band 15, mounted between rolls 16 and 17, of which the lower roll 16 is driven by a pinion 18, which meshes with a pinion 19, which in turn meshes with a gear upon the end of the grip-roll, thus effecting rotation of the endless band in contact with the grip-roll, and effectually stripping the skins from it.

It will be understood that my invention is not thus limited to the two specific means which I have disclosed, as other forms of rolls or devices by which the skins are stripped

from the grip-roll may be employed. It is, however, important that the stripping device, whatever its nature, be so placed as to afford an effective barrier to prevent any one standing in the rear of the machine from accidentally placing his hand in proximity to the point where the main roll 4 and the grip-roll 6 are turning inwardly together.

Having thus described my invention, I claim—

In a machine of the character described, the combination of the main roll; the grip-roll; an endless band in contact with both; and a stripping device for stripping the skins from the grip-roll, interposed in position to afford a barrier which prevents the hand of the workman from being placed in proximity to the point where the adjacent surfaces of the main roll and the grip-roll turn together.

In testimony whereof I have hereunto signed my name, at Philadelphia, Pennsylvania, this 23d day of March, 1905.

JAMES DUNN.
